CLAIM

The ornamental design for a sportsmen dream shelf, as shown and described.

DESCRIPTION

FIG. 1 is a front elevational view of a sportsmen dream shelf showing my new design; and,

FIG. 2 is a rear elevational view thereof.

The broken-line disclosure of shelves in the views is for illustrative purposes only and forms no part of the claimed design.

The article is understood to be of a conventional thickness.

1 Claim, 2 Drawing Sheets
